EDGAR S. HAYES, OF SEATTLE, WASHINGTON

VACUUM LOADER AND STACKER

Application filed October 31, 1929. Serial No. 403,892.

My invention refers to the canning art and more particularly to a device which is intended to handle a large number of cans at once for the purpose of moving them about or transferring them from one place to another. In canneries, more particularly in salmon canneries, it is necessary to handle the large number of cans filled daily, a number of times. In the past it has required a large amount of hand labor, as normally each can must be picked up by the hands of the workman one or two at a time, as for instance, when the cans come from the machine lines where they have been filled and the covers put in place, it is necessary to stack the cans on a truck where they are conveyed to the point of delivery and then rehandled again. This often takes place five or six times in the course of the various operations necessary to fill the can with produce and prepare it for its final delivery to the trade. In salmon canneries the cans are usually stacked in a metal frame work called a "cooler". This is done in order to make it possible to handle quite a large number of cans as a unit once they have been stacked thereon.

With the use of my device however, all hand handling of filled cans is eliminated.

Further, it is not necessary to use the metal coolers or trays which are expensive, are constantly needing repair and require a large amount of storage space when they are not in use. Therefore,

The principal object of my invention is to provide a device which will pick up a large number of cans without the need of hand handling the same.

A further object is to provide a device which will make the transportation of cans, for a limited distance, a very economical operation.

A further object is to provide a device that will permit the rapid handling of filled cans with the employment of the minimum amount of labor.

A further object is to provide a device which will be operable even though all the cans are not uniformly placed at the start of the operation and thus avoid unnecessary labor.

A still further object of my invention is to provide means for lifting a large number of cans, even though their upper surfaces may not form a single plane.

Other and more specific objects will be apparent from the following description taken in connection with the accompanying drawings, wherein

Figure 1 is an elevation of my device, partly in section to better illustrate certain parts.

Figure 2 is a detail in section of one of the can engaging members.

Figure 3 is a fragmentary view illustrating the valving arrangement for the control of my device.

Figure 4 is a fragmentary view showing one corner only of my machine in bottom plan view to illustrate the spacing and arrangement of my can engaging members.

Figures 5 and 6 are diagrammatic views illustrating the valve connections and the method of operation.

Referring to the drawings throughout which like reference numerals indicate like parts, numeral 10 designates the main body portion of my device. Separated slightly from member 10 by the distance piece 12, is the bottom plate 14. This separation provides for the chamber 16 which serves as a header to distribute either vacuum pressure or positive air pressure to the various tips. Secured into bottom plate 14 at regularly spaced intervals illustrated in Figure 4, such as will accommodate a desired size can, are a plurality of tips 18.

Referring to Figure 2, tip 18 has immediately below its threaded portion, a shoulder, which provides a definite stop when the tip is screwed in place. Holes 20 are provided for the engagement of a teat wrench. The lower end of tip 18 has an outwardly extending annular ledge 24 which supports a gasket 25. Surrounding the lower end 24 is a heavy slidable member 26, which is recessed so that the ledge 24 may have ample room for movement without becoming air bound as member 26 moves up and down. The upper end of member 26 is bored to provide a snug sliding fit on tip 18. A small hole 30 is

drilled approximately through the center of member 18. The bottom surface of member 26 is machined to accommodate the disk 34 which I normally prefer to make of a resilient material, such as rubber, although I believe it will be apparent that bakelite or micarta, or even spring metal might be employed. A plug member 36 is adapted to securely maintain the washer 34 in position and is provided with a feathered edge 38, which will prevent the metal of member 36 coming in contact with the can top when it is desired to use the device. Member 36 has a centrally drilled hole 40 and thus a passage way is provided clear through the device to the chamber 16. Plug 36 may engage member 26 in any manner that will provide a secure fastening. I have found that screwing member 36 in position by means of a teat wrench using the holes 42, is a very convenient method. I have found it desirable to use the same wrench on both members 18 and 36.

Secured, preferably centrally, with member 10 and extending upwardly therefrom, is a cylinder 44 having therein the piston 46 which may be of any conventional type and a piston rod 48. The upper end of piston rod 48 is formed as a hook or more preferable, as an eye 50, which is adapted to engage a traveling carriage 52 which may be supported from any conventional type of overhead trackage as indicated by 54.

In order to provide maximum rigidity with the minimum weight, I have provided a plurality of braces 56, which engage the fitting 58 at the upper end of cylinder 44, and are secured to body member 10 as by the cap screws at 60.

My machine, for its most successful operation, should be supplied with a pressure air line as 62 and a negative pressure or vacuum line 64. Both lines are controlled by the ordinary type of three-way valves 76 and 66 respectively. In order to facilitate the convenient manipulation of the valves of my machine, I provide tubes 68 and 70 respectively. The valves are controlled by revolving tube 68 or 70 upon their supporting brace members 56, which in turn transmit the necessary reciprocating motion to the handles 79 and 69 of the valves 76 and 66 respectively by means of the arms 72 and 73 which are fixedly secured to tubes 68 and 70 and the connecting bars 74 and 75.

A better understanding of the valving arrangement can be had by studying Figure 3. This shows the vacuum line valve 66 in its proper relationship to the vacuum line 64 and the pressure air line 62. Valve 76 is positioned diametrically opposite valve 66. In Figure 3 I have shown the connecting pipe 80 as straight, where in effect it is curved, in order to pass half around cylinder 44. Leading downwardly to chamber 16 is a pipe 81.

This pipe serves in turn to convey either negative pressure or positive air pressure according to the setting of valve 66. Valve 76 is provided with an upwardly extending pipe 83 which supplies air under pressure to the cylinder 44 where it acts on the piston 46. A short pipe 84 is also connected to the three-way valve 76, so I believe it will be apparent that valve 76 may be set to either pass air under pressure through pipe 83 to the cylinder or by the alternate setting, may discharge through pipes 83 and 84, any pressure that has been built up within cylinder 44.

In Figure 4 I have illustrated in some detail the most desirable location of the can engaging members. Cans in a cannery are normally stacked in staggered rows and it is only by so stacking them that uniform spacing, which is very desirable in the operation of my device, can be definitely assured.

Method of operation

In operating my device it is assumed that means have been provided for stacking the cans in staggered rows tight together. This may be accomplished by any one of the well known methods such as having a wide conveyor belt which carries the cans up against a stop. This part is normal cannery equipment and I have made no showing of it in my drawings.

Having the cans in the staggered row arrangement, my device is moved by any convenient means, as by the overhead trolley, illustrated to a place directly over the cans it is desired to move.

Valve 76 is then turned to the exhausting position permitting the trapped air in cylinder 44 to escape. This will lower the head member 10 until the rubber disks 34 are in engagement with the top of the cans.

Valve 66 is then turned to the position which will connect the vacuum hose 64 with pipe 81. A vacuum is then quickly created within the chamber 16, which in turn communicates it to the plurality of tips. This will cause the cans to adhere firmly to the can engaging members.

Valve 76 is now turned to a position which will admit air under pressure to cylinder 44. As the piston 46 is fixed in its horizontal relationship, the entire cylinder moves upwardly carrying with it all the cans adhering to the can engaging members.

The device complete with the adhering cans may now be transported about. When the desired new location for the cans has been reached, valve 76 is again operated to lower the entire machine until the cans come to rest. At this point the vacuum line is shut off by valve 66 and air from pipe 62 is passed through pipe 81 and the chamber 16. This gives a very quick contra-action and breaks the vacuum almost immediately. The machine may then be lifted by manipulating

valve 76 leaving the cans in their new position. One of the outstanding features of this method is that the cans will be placed in their new position in exactly the same relationship 5 and arrangement as that in which they were originally picked up and can thus be handled a number of times without any necessity for rearranging them.

I have found at times that for some reason 10 or another, oftentimes unevenness of floors, etc., all of the cans will not have their tops in the same horizontal plane and one of the objects of providing the automatic sliding adjustment of member 26 upon member 18 15 is to take up any such unevenness. This sliding feature is also an advantage in that the operator need not put any appreciable pressure on the top of the cans, as would ensue if the can engaging members were fixed 20 to the head 10.

Another point where attention to detail is essential, is the feature of having either hole 30 or hole 40 of rather small cross-sectional area, the reason being that oftentimes 25 there may be a blank space in a group of cans and by having the suction orifice 30 for instance, quite small, even though it be not covered, the loss in suction will not unbalance the system and cause all of the cans 30 to drop. In fact my device will operate with quite a number of cans missing. This small orifice in turn requires the air pressure to break the vacuum quickly as above described.

The foregoing description and the accompanying 35 drawings clearly disclose a preferred embodiment of my invention but it will be understood that this disclosure is merely illustrative and that such changes in the invention may be made as are fairly 40 within the scope and spirit of the following claims:

What I claim is:

1. A can handling device consisting of a body member; a bottom plate; a pressure 45 distributing chamber; a plurality of can engaging members having a tip provided with a small hole therethrough secured to said bottom plate; a slideable member disposed co-axially with said tip; a resilient disk and 50 a plug member having a small hole therethrough adapted to secure the disk to the slideable member; means adapted to produce a negative pressure at each can engaging member, a vacuum controlling valve, a fluid 55 pressure controlling valve, a source of fluid under pressure and means adapted to support the entire device.

2. A can handling device of the class described consisting of a body member; a bottom plate; a pressure distributing chamber; a plurality of can engaging members having a tip, provided with a small hole therethrough, secured to said bottom plate, a slideable member disposed co-axially with said 65 tip, a resilient disk and a plug member, hav-

ing a small hole therethrough, adapted to secure the disk to the slideable member; a piston; a piston rod; a cylinder secured to said body member and adapted to vertical movement; a three-way valve connected to the 70 vacuum line and the pressure fluid line in a manner capable of producing at will either a negative or positive pressure at each can engaging member; a source of fluid under pressure and means adapted to support the 75 entire device.

3. A can handling device consisting of a body member, a bottom plate spaced away from said body member to provide a distributing chamber; a plurality of tips secured to said bottom plate and communicating with said chamber; an annular ledge formed on each of said tips; a slideable member adapted to rest on said ledge and capable of sliding upwardly on said tip; a cupped 80 disc secured to said slideable member and providing a resilient engagement with an article to be raised; and a source of negative pressure.

In witness whereof, I hereunto subscribe 90 my name this 26th day of October, A. D. 1929.

EDGAR S. HAYES.
